UNITED STATES PATENT OFFICE.

SAMUEL EVERETT OAKES AND HELEN OAKES, OF PASSAIC, NEW JERSEY.

FOLDING CRIB OR CRADLE.

SPECIFICATION forming part of Letters Patent No. 628,350, dated July 4, 1899.

Application filed December 5, 1898. Serial No. 698,307. (No model.)

To all whom it may concern:

Be it known that we, SAMUEL EVERETT OAKES and HELEN OAKES, of Passaic, in the county of Passaic and State of New Jersey, have invented a new and Improved Folding Crib or Cradle, of which the following is a full, clear, and exact description.

Our invention relates to an improvement in cribs or cradles by which the same may be readily taken down or set up and when taken down may be packed away in a trunk, and thus readily transported from one place to another.

Our invention comprises the novel features of construction hereinafter described and claimed.

Reference is to be had to the accompanying drawings, forming a part of this specification, in which similar characters of reference indicate corresponding parts in all the figures.

Figure 1 is a perspective view showing the crib set up. Fig. 2 is a detail showing one of the rods or wires forming the bottom of the crib. Fig. 3 is a longitudinal sectional elevation of one end of the crib, and Fig. 4 is a plan view showing a modified construction of the bottom of the crib. Fig. 5 is an end view of our device folded.

The object of our invention is to construct a crib or cradle which shall be of light weight and which may be taken down and packed in a trunk or otherwise conveniently transported or stored. The end frames which support the device each consist of two bars A, pivoted to each other at A' and forming legs, said bars crossing each other and forming an X-shaped frame. At their lower ends the bars are preferably provided with rollers, as shown in Fig. 1, the bars being for this purpose given a quarter-turn, so that the rollers may be readily attached thereto, and the upper ends of the two legs are connected by a transverse bar D. This end bar D may be made in a single piece or be made in two pieces, connected by a rule-joint d at the middle of their length, as shown in Fig. 1. The latter construction will enable the crib to be readily folded up without taking it apart. The two end frames are connected by means of longitudinal bars, two of these bars, E, being connected with the upper ends of the legs A and the two other bars, C, being connected with

the lower portions of the legs. The bars E are reduced in diameter at their ends, as clearly shown in Fig. 3, and pass through holes which are formed in the upper ends of the legs A and the transverse bars D. They also pass through holes formed in the ends of the inclined bars B, which extend upward and meet above the center of the frame. The bars E and C are secured in position by means of nuts or buttons e, which are preferably made of some ornamental shape and which are threaded, so as to screw upon the threaded ends of the longitudinal bars. By this means the parts are securely clamped together and the frame made sufficiently rigid.

A longitudinal bar b connects the upper ends of the inclined bars B and also connects the bars at opposite ends of the frame, thus forming a ridge pole or bar, over which a mosquito-netting may be thrown when desired. The bottom, which supports the mattress or bedding, consists of a series of cross-bars F, which are preferably constructed as shown in Figs. 1 and 2, each cross-bar consisting of a wire having eyes f formed in each end thereof, the two eyes being preferably placed at right angles to each other. These cross-bars are hooked to each other, as shown in Fig. 1, the eye of one entering the eye of the next. These bars F are also preferably provided with a slight crimp or curve f' at their centers, so that the two bars which cross each other may have a slight engagement, which will hold them in proper relative position. The device thus forms a species of lazy-tongs which may be extended or folded, as desired.

A series of suspending-chains G is fastened in the eyes f at the ends of the cross-bars and extend upward, being provided at their upper ends with rings g, which slip over the longitudinal bars E of the frame. The chains G are preferably connected at a point near the middle of their length and near the rings g by longitudinal chains H and H', which prevent the chains G from being separated more than a certain fixed degree. At the ends a number of chains G' are attached to the transverse bars D and to the end cross-bars F, so as to prevent the bedding from escaping at the ends of the crib, these chains being similarly connected by the horizontal chains H and H'.

A modified form of construction of the bot-

tom is shown in Fig. 4 and consists of a series of cross-bars F', which are pivoted to each other by pins I at the center and by pivot-eyes J at their ends, so as to form a lazy-tongs. 5 At the ends transverse bars K are provided, these bars having slots k in each end, through which one of the pivot-eyes J passes. This permits the pivot-eye to slide as is required when the lazy-tongs are opened or closed. 10 These transverse bars are also provided with eyes J', to which, as well as to the eyes J, are connected the chains G, such as shown in Fig. 1 and previously described.

By removing the knobs or nuts e the whole 15 device may be quickly taken apart and folded up, so that it may be placed within any trunk which is long enough to receive the longitudinal bars E. The device may be made of very light construction and yet be of sufficient strength, so that its weight will not prohibit its being taken anywhere either in a trunk or by express. It is thus especially adapted for use by people who are traveling or who go to the country for the summer. If 25 it is desired to fold it up without taking it apart, this can be done by bending the bars D upward at their hinges, the bottom or mattress-support being disposed of by placing it vertically with one edge extending above the 30 rod E upon one side and beneath the rod E on the other side. For this purpose the length of the suspending-chains G should be not less than half the width of the crib.

Having thus fully described our invention, 35 we claim as new and desire to secure by Letters Patent—

1. A crib or cradle, comprising end frames each consisting of crossed and pivoted legs and a transverse bar connecting the upper 40 ends of said legs, longitudinal bars connecting the corresponding upper ends of the legs of opposite end frames, a mattress-support consisting of cross-bars, flexible suspending members as chains connecting the ends of 45 said cross-bars with the longitudinal rods, and means for limiting the spacing of the cross-bars, substantially as described.

2. A crib or cradle, comprising end frames each consisting of crossed and pivoted legs, 50 means for locking the legs in a fixed position, rods connecting the upper ends of the legs of both end frames, and a folding mattress-support consisting of cross-bars, flexible suspending members as chains connecting the ends 55 of said cross-bars with the longitudinal rods, and means for limiting the spacing of the cross-bars, substantially as specified.

3. A crib or cradle, comprising end frames each consisting of crossed and pivoted legs, 60 means for locking the legs in a fixed position, rods connecting the upper ends of the legs of both end frames, a folding mattress-support suspended from said rods, and consisting of cross-bars pivoted to each other to form 65 lazy-tongs, and suspension means connecting the ends of the cross-bars with the longitudi-

nal bars of the frame, substantially as described.

4. A crib or cradle, comprising end frames each consisting of crossed and pivoted legs and a transverse bar connecting the upper ends of said legs, longitudinal bars connecting the corresponding upper ends of the legs of opposite end frames, a mattress-support consisting of cross-bars provided with eyes at 70 each end, the eyes of one bar linking with the eyes of the adjacent bar and suspending members as chains connecting the ends of said cross-bars with the longitudinal rods. 75

5. A crib or cradle, comprising end frames each consisting of crossed and pivoted legs, means for locking the legs in a fixed position, rods connecting the upper ends of the legs of both end frames, and a folding mattress-support consisting of cross-bars provided with 80 eyes at each end, the eyes of one bar linking with the eyes of the adjacent bar, and suspension members as chains connecting the ends of said cross-bars with the longitudinal rods, substantially as described. 85

6. A crib or cradle, comprising a frame having longitudinal rods located one on each side, a mattress-support consisting of cross-bars, suspending members, as chains, connected with the ends of said cross-bars, and each containing a ring which embraces one of the longitudinal rods, and means for limiting the spacing of the cross-bars, substantially as described. 90

7. A crib or cradle, comprising a frame having longitudinal rods, one on each side, a mattress-support consisting of cross-bars provided with eyes at each end, the eyes of one bar linking with the eyes of the adjacent bar, and suspending members, as chains, connecting with the ends of said cross-bars and each containing a ring which embraces one of the longitudinal rods, substantially as described. 100

8. A crib or cradle, comprising end frames each composed of pivoted and crossed bars forming legs, a connection between the upper ends of said legs, consisting of bars constructed of two members pivoted to each other by a rule-joint, longitudinal bars connecting the end frames, a bed support or bottom, and flexible suspenders connecting the edge of the bottom with said longitudinal bars, said 110 suspenders being not less in length than half the width of the bottom. 115

9. A crib or cradle, comprising end frames each composed of pivoted and crossed bars forming legs, and a connection between the upper ends of said legs, consisting of two members pivoted to each other by a rule-joint, longitudinal bars connecting the upper ends 120 of the legs of each frame, a mattress or bed support and flexible suspenders connecting the longitudinal bars with the side edges of said bed-support, said suspenders being not less in length than half the width of the bed- 125 support. 130

10. A crib or cradle, comprising end frames

each composed of two pivoted and crossed bars forming legs, and a connection between the upper ends of said legs, consisting of two members pivoted to each other by a rule-joint, 5 longitudinal bars connecting the upper ends of the legs of each frame, a mattress or bed support and flexible suspenders connecting the longitudinal bars to the side edges of said bed-support, said suspenders being not less in 10 length than half the width of the bed-support, a bar extending longitudinally above the bed and forming a canopy-support, and two bars extending downwardly from each end thereof and pivoted to the upper end of the legs

whereby the whole may be folded, substantially as described. 15

11. A crib or cradle, comprising a supporting-frame having a longitudinal bar at each side and adapted to fold to bring these two bars together, a bed-bottom, and suspenders connecting the edges of the bottom with the longitudinal bars and equal in length to not less than half the width of the bottom. 20
